WALTER C. GREIST, ANDREW J. CARMICHAEL, AND PEACE R. FISCHER, OF NEW HAVEN,
CONNECTICUT, ASSIGNORS TO THE GREIST MANUFACTURING COMPANY, A COR-
PORATION OF CONNECTICUT

BINDING AND PIPING ATTACHMENT FOR SEWING MACHINES

Application filed April 23, 1929. Serial No. 357,563.

This invention has for its object to provide an improved sewing machine binder of such construction that one or more piping strips may be fed to the needle of a sewing machine with the binding, for enabling binding and piping to be simultaneously performed, and in which the piping guide plate and also, preferably, the binder scroll are laterally adjustable, all as will be hereinafter more fully explained.

In the accompanying drawings Fig. 1 is a plan view of the improved binding and piping attachment. Fig. 2 is a view similar to Fig. 1 but showing some parts in different positions. Fig. 3 is a side view of the attachment looking from the right of Figs. 1 and 2. Fig. 4 is a detail section on line 4—4. Fig. 1. Fig. 5 is a side view of the attachment looking from the left of Figs. 1 and 2.

Referring to the drawings, 12 denotes a presser-foot having a forked shank 13 by which it may be attached to the presser bar of a sewing machine. Attached to the presser-foot 12 by a rivet 14 is a plate 15 having a laterally extending part 16 provided with an open slot 17 and to which laterally extending part 16 the binder scroll 18 is suitably attached, preferably by soldering. This binder scroll is provided with a series of slots 19 of different heights or lengths for the purpose of accommodating bindings of different widths, or for the purpose of receiving both a comparatively narrow binding tape or strip and a relatively wide piping strip.

Also attached to the presser-foot 12 is a piping guide plate 20 having a series of slots 21 of different lengths to accommodate piping strips of different widths. The slotted portion of the said plate 20 is in line with, or on a level with the central opening in the binder scroll between the two lobes of said scroll, as shown in Fig. 5.

The plate 15, carrying the binder scroll 18, and the piping guide plate 20, are preferably adjustable laterally on the presser-foot 12, to which they are attached by the rivet 14. To this end the openings 15^a and 20^a in said plates, and through which openings the shank of said rivet passes, are somewhat elongated, and the needle openings 15^b and

20^b in said plates will also be somewhat elongated. The said plates are frictionally retained in any desired position to which they may be adjusted by a bowed spring 22 located beneath the head of said rivet 14 and bearing 35 on the plate 15.

For convenience in adjusting the plates 15 and 20 laterally said plate 15 may be provided with an upturned lug or finger piece 15^c, and the forward cross-piece 20^c of said plate 20 may likewise be provided with an upturned lug or finger piece 20^d. By pressing inward on the finger-piece 15^c the plate 15 and the binder scroll 18 carried thereby may be moved to the right, and by pressing inward on the finger-piece 20^d the piping guide-plate may be moved to the left, such lateral adjustment of these plates opening the slots 21 in the piping guide plate, as shown in Fig. 1, so that piping strips may 70 be inserted sidewise or edge-wise into said slots, if desired, instead of leading such strips through said slots end-wise.

By the lateral adjustment of the plate 15 and the binder scroll carried thereby, provision is made for bringing the line of stitching nearer to or farther from the edge of the binding, as will be understood. The lateral adjustment of the piping guide plate enables piping strips of a given width to be exposed 75 from under the edge of the binding for varying widths, and also accommodates, in such adjustment as is shown in Fig. 1, much wider piping strips than could be used in such adjustment of the piping guide plate as is 80 shown in Fig. 2.

In the operation of the improved binding and piping attachment a binding of any desired width may be led through one of the slots 19 in the binder scroll 18. If a narrow 90 binding be led through one of the scroll slots 19 in the binder scroll 18 and a wider piping strip be led through a larger slot in said scroll, the binding and piping may be simultaneously attached to the edge of a fabric 95 the right hand edge of which is extended into the binder scroll beneath the piping guide plate 20; and in such case the binding and piping will appear on both sides of the fabric edge. If, however, a plurality of fold- 100

ed piping strips of different widths be led through the slots 21 in the piping guide plate 20, and a binding strip be also simultaneously entered into the binder scroll 18, binding and multiple piping will be simultaneously performed by the use of this improved attachment, the pipings appearing on the upper side only of the work.

Pivots mounted on the plate 15 is an adjustable guide 23 which, however, forms no part of the present invention, as this feature is included in our application Serial No. 357,562, filed April 23, 1929.

From the foregoing it will be understood that by the use of this improved attachment binding and single or multiple piping may be simultaneously performed on a sewing machine.

The invention is not to be understood as being limited, in all of its details, to the particular constructions, herein shown and described, as such details may be varied widely, within the limits of mechanical skill, without departing from the scope of the invention.

Having thus described our invention we claim and desire to secure by Letters Patent:

1. A sewing machine binding and piping attachment comprising a laterally adjustable binder scroll having a series of slots of different sizes, for the accommodation of binding strips of different widths, combined with a piping guide plate having a plurality of piping guide slots of different lengths.

2. A sewing machine binding and piping attachment comprising a binder scroll having a series of slots of different sizes, for the accommodation of binding strips of different widths, combined with a laterally adjustable piping guide plate having a plurality of piping guide slots of different lengths.

3. A sewing machine binding and piping attachment comprising a presser-foot having a shank for attachment to a presser bar, combined with a laterally adjustable plate secured to said presser-foot, a binder scroll supported by said plate, and a piping guide plate having one or more strip guiding slots.

4. A sewing machine binding and piping attachment comprising a presser-foot having a shank for attachment to a presser-bar, combined with a plate secured to said presser-foot, a binder scroll supported by said plate, and a laterally adjustable piping guide plate having one or more strip guiding slots.

5. A sewing machine binding and piping attachment comprising a presser-foot having a shank by which it may be secured to the presser bar of a sewing machine, combined with a laterally adjustable binder scroll having a series of strip-guiding slots of different lengths, to accommodate binding strips of different widths, and a piping guide-plate having a plurality of strip-guiding slots of different lengths.

6. A sewing machine binding and piping attachment comprising a presser-foot having a shank by which it may be secured to the presser bar of a sewing machine, combined with a binder scroll having a series of strip-guiding slots of different lengths, to accommodate binding strips of different widths, and a laterally adjustable piping guide-plate having a plurality of strip-guiding slots of different lengths.

7. A sewing machine binding and piping attachment comprising a presser-foot having a shank by which it may be secured to the presser bar of a sewing machine, combined with a laterally adjustable binder scroll having a series of strip-guiding slots of different lengths, to accommodate binding strips of different widths, and a laterally adjustable piping guide-plate having a plurality of strip-guiding slots of different lengths.

8. A sewing machine binding and piping attachment comprising a binder scroll, combined with a piping guide plate having in one edge a plurality of piping guide slots, of different lengths, said piping guide plate being laterally adjustable to different working positions in a plane at a right angle to the length of said binder scroll.

9. A sewing machine binding and piping attachment comprising a piping guide plate having one or more piping guide slots in one edge, combined with a binder scroll which is laterally adjustable to different working positions nearer to or farther from the slotted edge of said piping guide plate.

10. A sewing machine binding and piping attachment comprising a piping guide plate having a plurality of piping guide slots of different lengths in one edge, combined with a binder scroll which is laterally adjustable to different working positions nearer to or farther from the slotted edge of said piping guide plate.

In testimony whereof we affix our signatures.

WALTER C. GREIST.
A. J. CARMICHAEL.
PEACE R. FISCHER.
